UNITED STATES PATENT OFFICE

WILLIAM C. HIERING, OF NEWARK, NEW JERSEY, ASSIGNOR TO J. E. MERGOTT CO., OF NEWARK, NEW JERSEY, A CORPORATION OF DELAWARE

DESIGN FOR A COMBINED DESK PAPER WEIGHT, CALENDAR, AND BLOTTER

Application filed October 3, 1930. Serial No. 37,119. Term of patent 7 years.

To all whom it may concern:

Be it known that I, WILLIAM C. HIERING, a citizen of the United States, residing in the city of Newark, in the county of Essex and State of New Jersey, have invented a new, original, and ornamental Design for a Combined Desk Paper Weight, Calendar, and Blotter, of which the following is a specification, reference being had to the accompanying drawing, forming a part thereof.

In the drawing:

Figure 1 is a plan view of a combined paper weight, calendar, and blotter, showing my new design, and

Figure 2 is a side elevation of the same.

I claim:

The ornamental design for a combined desk paper weight, calendar, and blotter, as shown.

WILLIAM C. HIERING.
